FLASH UNIT

Wallace A. Monson, Golden Valley, Minn., assignor to Honeywell Inc., Minneapolis, Minn., a corporation of Delaware

Filed Jan. 21, 1966, Ser. No. 716

Term of patent 14 years

(Cl. D61—1)

FIG. 1

FIG. 3

FIG. 2

FIGURE 1 is a front, top and side perspective view of a flash unit, showing my new design;

FIGURE 2 is an opposite side elevational view, to a reduced scale and

FIGURE 3 is a back elevational view to the same scale as FIGURE 2.

Portions of the drawing figures are shaded to indicate contrast in appearance.

I claim:

The ornamental design for a flash unit, substantially as shown and described.
